UNITED STATES PATENT OFFICE.

FRANK HENNEBÖHLE, OF CHICAGO, ILLINOIS.

ENGINE.

1,086,047.

Specification of Letters Patent.

Patented Feb. 3, 1914.

Application filed October 30, 1909. Serial No. 525,482.

To all whom it may concern:

Be it known that I, FRANK HENNEBÖHLE, a citizen of the United States, residing at Chicago, in the county of Cook and State 5 of Illinois, have invented certain new and useful Improvements in Engines, of which the following is a specification.

This invention relates to compound steam engines and its object is to provide a combined steam receiver and valve chest and an improved valve mechanism for compound engines.

In the accompanying drawings, Figure 1 is a sectional view, partly in elevation, of a 15 cross compound steam engine embodying the features of my invention. Fig. 1^a is a sectional detail illustrating the means for admitting steam to the high-pressure cylinder and for exhausting steam therefrom. Fig. 2 is a section on line 2 2 of Fig. 1. Fig. 3 is a section on line 3 3 of Fig. 2. Fig. 4 is a section of line 4 4 of Fig. 1. Fig. 5 is an enlarged sectional view of one of the 20 pistons. Fig. 6 is a detail view of a valve 25 which may be employed in said piston. Fig. 7 is a face view of one of the slide valves. Fig. 8 is a sectional detail view of said valve.

The embodiment selected for illustration comprises a high-pressure cylinder 1 and a 30 low-pressure cylinder 2, the combined receiver and valve chest 3 and the engine shaft 4. In each of the cylinders 1 and 2 are slidably mounted two pistons 5 and 6 arranged to move alternately toward and 35 from each other, steam being alternately expanded between the pistons and between each piston and the adjacent cylinder head. The pistons 5 and 6 are connected to diametrically opposite cranks upon the engine 40 shaft, the connection for the cylinder 5 consisting of a piston rod 7 and a connecting rod 8 extending between said piston rod and the crank 9. The connection between the piston 6 and the engine shaft consists in 45 this instance of two piston rods 10 and a connecting rod 11 joining each piston rod to a crank 12. The piston rod 7 extends through a packed central opening in the piston 6.

50 In Fig. 1 the valve is about to admit steam into the opposite ends of the cylinder 2, the pistons being about to commence their approaching movement under the expansive power of the steam. In such movement the cranks 12 are pulled upward and the crank

9 is pushed downward, the upward force exerted upon the cranks 12 being substantially equal to the downward pressure placed upon the crank 9. It will therefore be seen that the two forces tending to turn 60 the crank shaft are exerted in directly opposite directions and are substantially balanced. There is consequently practically no tendency to move the crank shaft against one side of its bearings and thus pounding 65 and friction in said bearings are reduced to a minimum. During such approaching movement of the pistons, there is an upward pressure on the upper cylinder head and a downward pressure on the lower cylinder 70 head. These forces, which are substantially equal and exerted in opposite directions, are resisted by the cylinder walls, no part of said forces being transmitted to the frame, base or foundations, which may therefore 75 be of minimum weight and strength.

When steam is admitted to the space between the pistons, the latter are forced apart, the crank 9 being pulled upward and the cranks 12 being pushed downward; consequently, during the separating movement of the pistons, as in the case of the approaching movement, the forces acting upon the shaft are substantially balanced and pounding and friction are substantially eliminated. 80 During the separating movement of the pistons, no pressure is exerted upon the cylinder heads.

In order to prevent the leakage of steam through the opening 13 in the piston 6, 90 through which the piston rod 7 passes, suitable packing may be provided. I have herein shown the piston as having therein a stuffing box or chamber 14 (Fig. 5) containing packing material 15, which packing 95 material is held in fluid-tight contact with the rod 7 by steam pressure. Steam is admitted to the chamber 14 through ports 16 and 17, a chamber 18 and a passage 19. Within the chamber 18 is a double valve 100 member 20 adapted to close either of the ports 16 and 17. Said valve member has guide stems 21 extending within the ports 16 and 17. When steam is admitted to the space between the pistons, steam enters the 105 port 16, forces the valve member 20 into position to close the port 17, and passing through the duct 19 enters the chamber 14 and presses the packing material 15 against the rod 7. When steam is admitted to the 110

space between the piston 6 and the adjacent cylinder head, the steam enters the port 17, closes the port 16 and enters the chamber 14. Steam pressure may also be used to hold 5 the piston packing 22 against the cylinder walls by connecting the groove 23 in which said packing is mounted with the chamber 18 by means of a duct 24.

For each of the cylinders 1 and 2 there 10 is provided, in the combined receiver and valve chest, a slide valve 25 arranged to be reciprocated over the valve face 26. Said face is connected with the space between the pistons by a port 27, with the ends of the 15 cylinder by ports 28 29 30, and with the exhaust 31 or the steam supply pipe 32, as the case may be, by a port 33. The valves 25 are mounted at opposite sides of a web or backing 34. 20 Each valve 25 is provided with a short stem 35, said stems being attached through the medium of a yoke 36 with a valve rod 37 which is connected through a reversing link motion 38 with the eccentrics 39 on the 25 shaft 4. The rod 37 extends through a stuffing box structure 45, the attaching portion of which is seated in a threaded opening 46 in the wall of the steam receiver. Similar 30 openings 47 48 are provided in said wall for use when it is desired to move the valves 25 by means of individual eccentrics, as when the cranks of one engine are set ninety degrees ahead of the cranks of the other. When not in use the openings 47 48 are 35 closed by screw plugs 49.

Upon the rear side of each valve 25 is an annular flange 39 with which the flange 40 of a disk 41 telescopes. In the chamber 42 formed between the valve and the disk 41 40 is a coiled spring 50 assisting to hold the valve against the valve face and the disk 41 against the backing 34. The chamber 42 communicates with the working face of the valve 25 through ports 51. The fluid pressure 45 upon the side of the disk 41 toward the valve is balanced by pressure admitted to a shallow recess 52 in the opposite side of said disk through a port 53.

I desire to call attention to the fact that 50 the steam receiver 3 is located between the cylinders and may be formed integral with said cylinders. The receiver 3 also serves as a valve chest. This construction conduces greatly to compactness and cheapness, and 55 reduces condensation to the minimum.

High pressure steam is admitted internally of the valve for the high-pressure cylinder, steam being exhausted from said cylinder externally to the valve and directly 60 into the receiver. Low pressure steam is admitted to the low-pressure cylinder externally of the valve for said cylinder, steam being exhausted from said cylinder internally of the valve and to the pipe 31.

65 In order that steam at an increased pres-

sure may be supplied to the low-pressure cylinder, I provide a by-pass 43 in which is located a regulating valve 44 of any approved construction, whereby steam at the desired pressure may be admitted to the receiver 3. 70

I claim as my invention:

1. The combination of a high-pressure cylinder, a low-pressure cylinder, a single combined steam receiver and valve chest directly connected by ports to said cylinders, valve means in said combined steam receiver and valve chest for controlling the flow of steam in said ports and means for admitting high-pressure steam internally of 80 the valve for the high-pressure cylinder. 75

2. The combination, in a cross-compound engine, of a high-pressure cylinder and a low-pressure cylinder arranged side by side, a single combined steam receiver and valve 85 chest located directly between said cylinders and directly connected by ports to said cylinders, valve means in said combined steam receiver and valve chest for controlling the flow of steam in said ports and means for admitting high-pressure steam internally of 90 the valve for the high-pressure cylinder. 95

3. The combination of a high-pressure cylinder, a low-pressure cylinder, a combined steam receiver and valve chest located between said cylinders and operatively connected by ports to said cylinders, a valve member in said combined receiver and valve chest for each of the cylinders, means for admitting steam internally to the high-pressure 100 valve, the high-pressure cylinder exhausting into the receiver externally of the high-pressure valve, the low-pressure valve admitting steam externally of itself from the receiver to the low-pressure cylinder, and 105 exhausting steam from the low-pressure cylinder internally of said low-pressure valve. 100

4. The combination of two cylinders arranged in parallelism, a combined steam receiver and valve chest connected by ports to 110 said cylinders, a web within said receiver, a single valve for each of said cylinders, said valves being slidably supported by said web, and means for reciprocating said valves. 115

5. In a compound engine, the combination 115 of a high-pressure cylinder; a low-pressure cylinder; a shaft; opposed cranks on said shaft for each cylinder; two pistons in each cylinder connected to said cranks to move in opposite directions; a combined steam receiver and valve chest directly connected by ports to said cylinders; and a single valve for each cylinder located in said combined steam receiver and valve chest and operated from said crank shaft. 120

6. In a cross-compound engine, the combination of a high-pressure cylinder and a low-pressure cylinder arranged side by side; a crank shaft; pistons in said cylinders connected to said crank shaft; a valve for each cylinder 125 130

der; eccentric means on said shaft for operating said valves, there being only sufficient space on said shaft between the engines to receive said eccentric means; and a single combined steam receiver and valve chest located directly between the cylinders and directly connected by ports to said cylinders, said

valves being located in said combined steam receiver and valve chest.

FRANK HENNEBÖHLE.
